United States Patent Office

Des. 184,181
Patented Dec. 30, 1958

184,181

CLOCK

George P. Lewis, Mineola, N. Y.

Application July 31, 1957, Serial No. 47,163

Term of patent 14 years

(Cl. D42—7)

FIG.1.

FIG.3.

Fig. 1 is a front elevational view of a clock embodying my design;

Fig. 2 is a top plan view of the same; and

Fig. 3 is a rear view of the same on a reduced scale.

I claim:

The ornamental design for a clock, substantially as shown.
